Primary Examiner—Cathy Anne MacCormac

[57] CLAIM

The ornamental design for a saddle attachment for protecting leg and calf, as shown and described.

DESCRIPTION

FIG. 1 is a front elevational view of a saddle attachment for protecting leg and calf showing my new design; FIG. 2 is a right side elevational view thereof; FIG. 3 is a top plan view thereof showing the strap folded over for ease of illustration; FIG. 4 is a left side elevational view thereof; FIG. 5 is a rear elevational view thereof; and, FIG. 6 is a bottom plan view thereof showing the strap folded over for ease of illustration. The dashed lines in FIG. 5 represent conventional stitching.

FIG. 1

FIG. 2

FIG. 3

FIG. 4

FIG. 5

FIG. 6
